UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

TRUNK CONSTRUCTION.

Application filed March 29, 1924. Serial No. 702,833.

This invention relates to improvements in trunk construction more particularly of the wardrobe type.

Wardrobe trunks of the usual type are formed of two hinged together sections which stand on end and swing horizontally to open or closed position. The two sections usually, a wardrobe section and a drawer section, abut each other and one of the sections is provided with a valance strip which overlaps the adjacent abutting edge of the other section. As thus constructed the overlapped section edge is not protected against pressure inwardly with the result that in use the sections are often broken, and if out in a storm the moisture gets into the trunk at the joint. The drawer section is generally provided with sliding drawers and the front upper edges of these drawers are usually very weak and break easily.

It is one of the objects of the present invention to overcome the before mentioned objectionable feature and provide a trunk construction in which the parts are so formed and reinforced as to prevent the parts going under strain, and to prevent the moisture from passing into the trunk through the joints thereof.

A further object of the invention is to provide a trunk construction in which a metal groove or recess is provided in the lower edge portion of the drawer section into which the lower edge of the wardrobe section swings to form a close connection therewith.

A further object of the invention is to provide a trunk which is of very simple construction, is strong and durable and is well adapted for the purpose described.

With the above and other objects in view the invention consists of the improved trunk construction and its parts and combinations as set forth in the claims, and all equivalents thereof.

In the accompanying drawing in which the same reference characters indicate the same parts in all of the views;

Fig. 1 is a front view of a wardrobe trunk embodying the improved construction, the trunk sections being shown in open position;

Fig. 2 is a vertical sectional detail view taken on line 2—2 of Fig. 1 on a larger scale;

Fig. 3 is a horizontal sectional detail view taken on line 3—3 of Fig. 2;

Fig. 4 is a sectional detail view taken on line 4—4 of Fig. 3; and

Fig. 5 is a sectional perspective view of the front upper portion of one of the trunk drawers provided with the reinforcement.

Referring to the drawing the numeral 8 indicates the wardrobe section and 9 the drawer section of a wardrobe trunk embodying the improvements. The two sections are hinged together to swing horizontally to closed or open position and the wardrobe section is provided with a hinged top cover 10 to permit convenient access to garments which may be suspended from hangers 11 slidably mounted within said wardrobe section. The other section of the trunk is provided with slideable drawers 12.

The two trunk sections have their edge portions 8 and 9 abutting when in closed position and the drawer section 9 is provided with a valance strip 13 which overlaps the adjacent edge of the wardrobe section. Said last mentioned edge is reinforced with a U-shape in cross section valance strip 14. A reinforcing strip 15 is mounted on the inner surface of the lower portion of the drawer section and projects outwardly therefrom to overlap the edge of the wardrobe section as clearly shown in Fig. 4. As thus positioned a groove 16 is formed along the lower edge of the drawer section into which the edge portion 8' of the wardrobe section extends to form a tight closure. Said reinforcing strip 15 is secured to the drawer section by rivets or tacks 17 and at points adjacent the opposite sides of the said section portions 15' are turned downwardly to engage the edge 9' of the drawer section to accommodate reinforcing angle members 18 mounted on the inner opposite sides of the wardrobe section 8. Said strips reinforce the sides of the trunk and also serve to hold the drawers of the other section in place.

The inner upper front portion 12' of each drawer 12 is reinforced by a strip of metal 19 which extends across the entire front portion of the drawer and is secured thereto by rivets 20. Said strip is folded or corrugated to form a double rib 19' and flanges 21 through which the rivets 20 extend to attach the strip to the drawer as shown. The reinforcing strips 19 prevent the front portions of the drawers from warping and also coact with the angle members 18 in preventing the weight or pressure of the contents of the drawers from forcing the medial portions of the front parts of the drawers outwardly.

The reinforcing strip 15 is provided with a central slot 22 to receive the lower end of the drawer lock bar 23 which is positioned in front of the drawers and its upper end is 5 locked to the upper part of the drawer section, thus forming a firm support for the lower end of said bar.

From the foregoing description it will be seen that the trunk construction is well reinforced in a very simple manner. Furthermore the grooved joint at the lower portion 10 keeps moisture from entering the lower portion of the trunk.

What I claim as my invention is:

15 1. A trunk construction, comprising a wardrobe section and a drawer section having bottom portions and adjacent non-yielding edge portions, a non-yielding valance member mounted on the edge portion of one 20 of the sections and overlapped by the adjacent edge portion of the other section, and a reinforcing strip mounted in the bottom portion of the trunk section provided with the valance member and spaced above the valance member to form in combination with the valance member and the front edge of the drawer section a groove, the opposite end portions of the reinforcing strip having parts extending downwardly in front of the 25 lower edge of the said section and engaged by the edge of the other section.

2. A trunk construction, comprising a wardrobe section and a drawer section having drawers therein, a non-yielding valance 30 member mounted on the outer edge portion

of the drawer section and overlapped by the adjacent non-yielding outer edge of the wardrobe section, and a non-yielding reinforcing strip mounted in the lower inner side portion of the drawer section and spaced 40 from the valance member to form in combination with the valance member and the front edge of the drawer section a groove into which the lower edge portion of the wardrobe section extends, said reinforcing strip 45 also having opposite end and downwardly extending portions against which the edge of the other section abuts.

3. A trunk construction, comprising a wardrobe section and a drawer section having drawers therein, a non-yielding valance member mounted on the edge portion of the drawer section and overlapped by the adjacent non-yielding edge of the wardrobe section, a non-yielding reinforcing strip mounted on the lower inner side portion of the drawer section and spaced from the valance member to form in combination with the valance member and the front edge of the drawer section a groove into which the lower 50 edge portion of the wardrobe section extends, said reinforcing strip having opposite end and downwardly extending portions against which the edge of the other section abuts, said reinforcing strip having an opening 55 medially of its length to accommodate the lower end of a locking bar.

In testimony whereof, I affix my signature.

JULIUS RITTER, JR.
